UNITED STATES PATENT OFFICE.

JOSEPH SOHN, OF NEW YORK, N. Y.

DESIGN FOR A LAMP PEDESTAL OR OTHER SIMILAR ARTICLE.

Application filed May 29, 1924. Serial No. 9,746. Term of patent 7 years.

To all whom it may concern:

Be it known that I, JOSEPH SOHN, a citizen of the United States, and a resident of the city of New York, borough of Manhattan, in the county and State of New York, United States of America, have invented a new, original, and ornamental Design for a Lamp Pedestal or Other Similar Article, of which the following is a specification, reference being had to the accompanying drawings, forming part thereof.

The figure is a perspective view of a lamp pedestal or other similar article, embodying my design.

I claim:

The ornamental design for a lamp pedestal or other similar article, as shown.

JOSEPH SOHN.
